US0D1076974S

(12) **United States Design Patent** (10) **Patent No.:** **US D1,076,974 S**
(45) **Date of Patent:** **** May 27, 2025**

(54) **COMPUTER SCREEN WITH GRAPHICAL
USER INTERFACE**

(71) Applicant: **Spotify AB**, Stockholm (SE)

(72) Inventors: **Mateo Rando**, Stockholm (SE); **Matt Turnbull**, London (GB); **John Lanyon**, London (GB)

(73) Assignee: **Spotify AB**, Stockholm (SE)

(**) Term: **15 Years**

(21) Appl. No.: **29/866,047**

(22) Filed: **Aug. 25, 2022**

Related U.S. Application Data

(62) Division of application No. 29/774,684, filed on Mar. 18, 2021, now abandoned, which is a division of application No. 29/609,097, filed on Jun. 28, 2017, now Pat. No. Des. 917,499.

(57) **CLAIM**

The ornamental design for a computer screen with graphical user interface as shown and described.

DESCRIPTION

FIG. 1 is a front view of a computer screen with graphical user interface; and,

FIG. 2 is a front view of a second embodiment thereof. The dot-dash lines in the Figures represent a boundary of the claimed design and a computer screen and form no part of the claimed design.
